UNITED STATES PATENT OFFICE.

CHARLES P. BALGER, OF CINCINNATI, OHIO.

ARTIFICIAL DENTURE.

1,071,019.

Specification of Letters Patent. Patented Aug. 26, 1913.

Application filed December 27, 1912. Serial No. 738,856.

To all whom it may concern:

Be it known that I, CHARLES P. BALGER, a citizen of the United States, and a resident of Cincinnati, county of Hamilton, and 5 State of Ohio, have invented a new and useful Improvement in Artificial Dentures, of which the following is a full, clear, and exact description, reference being had to the accompanying drawings, forming a part 10 of this specification.

My invention relates to artificial dentures of the type in which the teeth are attached to a plate adapted to fit upon and engage the dental ridge of the patient's mouth.

15 Dental plates of various well-known types are now provided, with satisfactory results in some cases, but which, in other cases, prove unsatisfactory, either because they do not serve rigidly to retain the denture in 20 its proper position, or because of the discomfort which their use occasions. Especially where the dental or alveolar ridge is low, or flat, is the patient subjected to the annoyance of either one or both of these 25 defects.

The object of my invention is to overcome the defects above mentioned and to provide a plate for artificial dentures which will assure satisfactory results in all cases, means 30 being provided rigidly to secure the plate to the dental ridge without discomfort to the wearer regardless of the conformation of the mouth and dental ridge of the patient.

With such object in view my invention 35 consists in details of construction herein-after fully set forth.

In the drawings:—Figure 1 is a top view of an upper plate; Fig. 2 is a similar view of a slightly modified form of the same 40 plate; Fig. 3 is an elevation of an upper denture; Fig. 4 is a section of the upper denture; Fig. 5 is a view of the under side of a lower plate; Fig. 6 is a section of said lower plate.

45 The numeral 1 indicates the plate, either upper or lower, to which the teeth are attached. Said plate may be made of any suitable material and the teeth attached in the usual manner. The feature of my invention 50 consists primarily in providing said plate with a low ridge, or rib, of soft, elastic material, preferably rubber, said rib being indicated throughout the drawings by the numeral 2. As clearly shown in the sev-

eral figures of the drawings, the rib 2 borders the alveolar ridge cavity 3 of the plate and is located, on the rear side of the plate, near the upper edge thereof, but at such a distance therefrom that said edge may, when the plate is in position in the mouth of the 60 patient, come in contact with the mouth roof, thus protecting the rib of soft rubber and preventing the accumulation of food and saliva about the same. In the construction shown in Fig. 1, the rib extends only 65 around the heels 4—4 of the plate, the front portion of the plate being slightly thicker than the other parts thereof, as shown at 5, to form a counter-abutment on the front of the alveolar ridge to increase the grip and 70 adhesion of the plate. In certain cases, however, it is desirable to employ the modified form of the rib shown in Fig. 2, in which the rib extends entirely around the alveolar ridge cavity of the plate; on the 75 front side, however, being located but slightly above the lowest portion of said cavity, as clearly shown in Fig. 4. When the rib 2 extends entirely around the plate, the counter-abutment 5 of the plate may be 80 dispensed with if desired, as it may also, in certain cases, where the rib is only partial.

The employment of the rib 2 on the lower denture, as shown in Figs. 5 and 6, is the same as in the case of the upper as above 85 set forth, except that I prefer generally to have the rib 2, in a lower plate, extend entirely around the alveolar ridge cavity of said plate.

The operation of my invention will be 90 apparent from the foregoing description. The rib 2, in conjunction with the general formation of the plate, or in conjunction with the counter-abutment 5 and the plate, will create a suction to engage the alveolar 95 ridge of the wearer, thus firmly securing the artificial denture in its proper position; and the rib 2 being of soft, elastic material will not bite into the gums of the patient and will not, therefore, cause soreness and 100 discomfort. Furthermore, the rib, from its location is protected by the hard parts of the plate, and its durability is thus largely increased, while, at the same time, the condition of the plate, from a sanitary standpoint, is much improved over the condition 105 of a plate in which a soft, or elastic, suction device is used in an exposed position.

Having thus described my invention, what I claim as new and desire to secure by Letters Patent, is:

In an artificial denture, the combination 5 with a plate of an elastic rib on said plate, said rib being adapted to grasp the alveolar ridge on the lingual side thereof, and a

counter-abutment adapted to abut against the alveolar ridge on the labial side thereof in opposition to said rib.

CHARLES P. BALGER.
